UNITED STATES PATENT OFFICE.

FRANK P. COX, OF LYNN, MASSACHUSETTS, ASSIGNOR TO THE GENERAL ELECTRIC COMPANY, OF NEW YORK.

COIN-CONTROLLED MECHANISM.

SPECIFICATION forming part of Letters Patent No. 660,810, dated October 30, 1900.

Application filed April 8, 1899. Serial No. 712,208. (No model.)

To all whom it may concern.

Be it known that I, FRANK P. COX, a citizen of the United States, residing at Lynn, in the county of Essex and State of Massachusetts, have invented certain new and useful Improvements in Coin-Controlled Mechanism, (Case No. 829,) of which the following is a specification.

The present invention relates to coin-controlled mechanisms, and has for its object to improve their constructions.

The invention is directed more particularly toward the means employed for insuring the opening and closing of the circuit of prepayment-meters or other electric devices at predetermined times.

In the accompanying drawings, which show an embodiment of my invention, Figure 1 is a front elevation of a meter with the casing shown in dotted lines. Fig. 2 is a side elevation of the meter, the casing being shown in dotted lines, as before. Fig. 3 is a detail view showing the switch for making and breaking the circuit, and Fig. 4 is a diagram of connections.

The invention is shown in connection with one of the well-known Thomson recording wattmeters, in which A represents a supporting frame for the various parts of the meter.

30 A' is the main shaft, and mounted thereon is an armature A² and a damping-disk A³. The armature is mounted for revolution between the stationary field-coils A⁴, which are included in the main circuit, and the damping-disk is mounted for rotary movement between the poles of the damping-magnets A⁵. On the upper end of the armature-shaft is a worm A⁶, and meshing with this worm is a worm-wheel A⁷, which is connected by suitable gearing with the registering mechanism and the indicating hand or pointer A⁸.

Mounted on the front of the meter-frame A is a coin-controlled device for regulating the action of the meter. This device consists of a main coin-chute B and a secondary coin-chute B', the latter being provided with a slot in the front to show the number of coins contained therein, and between the two portions of the coin-chute is a rotary coin-receiver B². The coin-receiver is provided with a receptacle for receiving the coin after

it is inserted in the chute B and a coiled spring b for returning it to the normal position as soon as the coin has been deposited in the secondary coin-chute B'. The object of this 55 device is to prevent the insertion of improper articles into the coin-chute for the purpose of actuating the meter. The secondary coin-chute B' extends transversely across the front of the meter, and the right-hand end is 60 slightly lower than the left-hand end and is curved downward, so that the coins always have a tendency to move toward the right and drop into engagement with the rotary coin-wheel C and the flexible spring D. The 65 coin-wheel C is not included in the circuit, as will be seen by reference to Fig. 4. The flexible spring D, situated at the right of the coin-wheel, is connected to one side of the circuit, and at its lower end is provided 70 with a silver contact, which is arranged to establish connection with the fixed contact E when a coin passes from the coin-slot B' and rests between one of the arms of the coin-wheel C and the contact D. The circuit 75 connection of this particular feature of the meter will be described hereinafter.

The coin-wheel C is mounted on a shaft which is provided with suitable bearings, and meshing with the arms of this wheel is a four-arm cam-wheel F. The arms of the wheel F are enlarged at their outer ends to form cams, and these cams engage with the arms of the wheel C and regulate its motion. The cam-wheel F is mounted on a shaft F', and carried by the shaft is an arm or pointer A⁸, which is designed to indicate the movements of the meter mechanism.

I do not claim the construction and arrangement of the coin-wheel C and the arm-wheel F, since it is the invention of Charles E. Holmes and is shown and claimed in application Serial No. 675,236, filed March 26, 1898.

Situated below the coin-wheel C and to the 95 left of the coin-slot is a pair of contacts G and G'. The former consists of a long thin piece of spring metal and is connected to one side of the circuit, while the latter consists of a fixed piece of metal and is connected by 100 a suitable wire to the opposite side of the circuit. The arrangement of the contacts and

coin-chute above referred to is such that the coin first closes the circuit between the contacts D and E, and later the same coin closes the circuit between contacts G and G'. When 5 only a single coin is deposited in the meter, the closing of the circuit between contacts D and E energizes the magnet H, which closes the main circuit of the meter. After the consumer has received the prepaid amount 10 of energy, the rotation of the coin-wheel C permits the coin to drop and open the circuit between the contacts D and E, the main circuit, however, still remaining closed. The next instant the coin drops on the flexible 15 contact G and by its weight closes the circuit through the releasing-magnet O'. As soon as this is done magnet O' is momentarily energized and the tripping mechanism is released in a manner more fully described 20 hereinafter. In other words, the armature of the meter constitutes an automatic register-controlling device and drives the coin-wheel to a point where it releases the coin and the latter again becomes operative by closing 25 the circuit of the releasing-magnet. When two or more coins or other tokens are on deposit in the apparatus at the same time, the first coin is released by the coin-wheel C when the prepaid amount of energy has been 30 consumed; but before it can drop to a point where it will close the circuit between the contacts G and G' the second coin has advanced to a point where it closes the circuit of the magnets H. This prevents the interruption 35 of the main circuit.

The coin-actuating mechanism of the meter and also the gearing are supported by the back plate B³, and this plate is supported by a number of lugs A⁶, projecting outward 40 from the meter-frame A. The plate being secured in place by screws it is a very simple matter to remove the entire mechanism either for inspection or repairs. A second plate B⁴, parallel with the first and secured 45 thereto by screws, affords a support for the coin-chute and other parts of the prepayment mechanism. The main and secondary coin-chutes are formed in the casting I, which is secured to the front of the plate B⁴ by screws. 50 This arrangement permits the ready assembling or taking down of the various parts.

The gearing for operating the pointer F may be of any suitable construction and is located between the plates B³ and B⁴.

55 Mounted on the insulating-support is an L-shaped bar J of magnetic material. This bar forms the yoke between the cores of the magnets H. The cores of the magnets are provided with conical tips which extend 60 through the movable armature H'. This arrangement permits a wide range of movement of the armature with a substantially-constant pull.

The support K is made of fiber or other insulating material and is retained in place by screws K', which enter lugs projecting from 65 the meter-frame.

Mounted on the support K is the armature H' of the magnets H. The means employed for supporting the armature consist of a thin strip of spring metal L—such as phosphor-bronze, for example—which strip is bent downward at right angles to the plane of the armature and is secured to the support by screws. A part of the piece L is bent downward, as shown at l, to provide an additional spring to raise the armature to the position shown, and by moving the screw l' in or out the tension of the spring l can be adjusted. On the outer end of the strip L is a spring-contact L'. In the present instance this contact is made of silver, since it makes better contact and is not so liable to corrode as other metals. Situated directly below the contact is a second contact M, also covered with silver, which is carried by a small plate mounted on the top of the left-hand magnet H. Mounted on the bar J is an L-shaped piece of non-magnetic material N, and secured thereto is a small magnetic blow-out N' for disrupting any arc which may be formed when the circuits between the contacts L' and M are interrupted. This magnet is of the horseshoe type and is energized by a winding that is included in the main circuit of the meter.

Mounted on the top of the insulated plate K is a bracket O, and secured to the bracket is an iron-clad shunt-wound magnet O². This magnet is provided with an armature O', having a horizontal movement, which armature is arranged to release the armature H' and permit the contacts L' and M to separate. Secured to the front of the armature is a bifurcated arm O³. (Best shown in Figs. 2 and 105 3.) Pivoted mounted on the head of left-hand magnet H is a latch P. This latch is composed of two hooks connected by a rod P'. The rod P' also serves to connect the outer ends of the bifurcated arm O³. Mounted 110 on the top of the armature H' and supported by posts h is a plate h', the latches P and plate h' being so arranged that they will engage when the magnets H are energized and the armature H' moved downward to a point 115 where it closes the circuit between the contacts L' and M. Between a stud Q, mounted on the upper head of the left-hand magnet H, and the armature O² of the releasing-magnet is a spring Q'. This spring is designed to 120 pull the armature O² to the left and force the latches P over the plate h' in order to hold the contacts of the main circuit in their closed position.

Situated in the lower right-hand corner of 125 the meter and directly under the secondary coin-chute B' is a tubular coin-receiver R. This receiver is held in position by a pivoted plate R', located beneath the meter and retained in place by a wing-nut R², which nut 130 can be sealed in place in the ordinary manner to prevent tampering with the meter.

Referring to Fig. 4, the circuit connections of the meter will be described.

1 and 2 represent supply-mains, and 3 and 4 the house-mains, supplying current to the lamps or other translating devices 5. Current enters through the main 1 and passes through the winding on the blow-out magnet to contact M, thence to contact L' and the spring-plate L, located on top of the armature H', through the field-coils A⁴ to the house-main 3. The circuit from main 2 is to the strip S, located in the back of the meter, to the house-main 4. The armature A² of the meter is connected between point 6 and the strip S. In other words, it is connected in shunt to the house-mains. In circuit with the armature is a starting-coil 7, furnishing an initial field, and a resistance 8 for reducing the amount of current flowing in the circuit, which is mounted in an envelop 8' and placed in the back of the meter. The magnet H is employed to close the main circuit of the meter and also that of the consumer, and its winding is connected to wire 9 on one side and to contact E on the other. Contact D, which forms a part of the last-mentioned circuit, is connected, when a coin is placed in the meter, to the strip S through a resistance 10 and wire 11. The resistance 10 is wound on a spool and is secured to one of the vertical side frames of the meter. The magnet O', for releasing the armature H' when it is desired to interrupt the circuit of the meter, is connected between point 12 on wire 9 and the fixed contact G'. The circuit is completed through the flexible contact G, resistance 10, wire 11, and strip S. By this arrangement I am enabled to use a single resistance for reducing the current in both the magnets H and O'. I have found that in meters of this class it is preferable to have one magnet for positively insuring the closing of the circuit, and a second magnet for positively insuring the opening of the circuit. With the parts arranged as shown in the diagram the main circuit is closed and the coin 13 is held between the coin-wheel C and the flexible contact D. The coin is released by reason of the rotation of the cam-wheel F and the arm-wheel or coin-receiver C, due to the operation of the meter. When the coin drops, the spring of contact D is sufficient to cause the interruption of the circuit at that point, and consequently the magnet H becomes deenergized. The spring-plate L is not, however, permitted to raise the armature H' and open the main circuit until the magnet O' is energized. When the coin drops from the position shown, and prior to falling into the coin-receptacle R, it strikes the contact G and momentarily closes the circuit through the releasing-magnet O'. As soon as this magnet is energized it attracts the armature O² against the action of the spring Q' and causes the latch P to release the plate h', and the armature H' moves upward due to the spring-plate L. This causes the contacts L' and M to separate and inter-

rupt the circuit of both the meter and the consumer. The magnet N' quickly disrupts any arc which may be formed at that point.

It will be seen that the coins do not form a part of an electric circuit. This I have found to be a desirable feature, since it prevents all burning of the coins which might be occasioned if the coin acted as a part of the circuit. It will also be seen that by the arrangement shown the currents handled by the contacts will be so small as to decrease the danger of arcing, and consequently the burning, to a minimum.

By the arrangement described and illustrated I am enabled to provide a main switch of sufficient size to handle the current flowing through the meter to the consumption-circuit without introducing any friction into the operation of the meter, and, as described in the Holmes application above referred to, the weight of the coin is utilized to overcome any friction of the coin and cam-wheels. I am also able to get any desired amount of energy for opening or closing a switch or switches, since the magnets can be wound to produce any desired result.

In practicing my invention it is unnecessary to follow the arrangement shown in the drawings, since the invention can be applied to any sort of device which is wholly or partially electric where it is desired to positively open and close an electric circuit. The invention may be advantageously applied where the coin forms a part of the principal or a secondary circuit or where the coin is out of circuit and its weight is utilized to close the main circuit.

So far as I am aware I am the first to provide a prepayment mechanism in which a magnet is employed for closing a circuit and a second magnet for opening the circuit, both of the magnets being under the direct control of a deposited coin or token.

What I claim as new, and desire to secure by Letters Patent of the United States, is—

1. In a coin-controlled mechanism, the combination of an electric circuit, a circuit-breaker included in the circuit, magnetically-controlled means for controlling both the opening and the closing of the circuit-breaker, a coin-controlled device for causing the closing of the circuit-breaker, and a separate device also coin-controlled for causing the opening of the circuit-breaker.

2. In a coin-controlled mechanism, the combination of an electric circuit, a switch included in the circuit, a magnet for causing the closing of the switch, a second magnet for causing the opening of the switch, and a coin-controlled means which is so arranged that the coin causes the energizing of first one magnet and then the other.

3. In a coin-controlled mechanism, the combination of an electric circuit, a switch included in the circuit, a magnet for causing the closing of the switch, a second magnet

- for causing the opening of the switch, and a coin-controlled means which is so arranged that it first causes the closing of the circuit, and then the opening of the circuit, a single coin causing both operations.
4. In a mechanism controlled by a coin or other token, the combination of a circuit, a switch in the circuit, a magnet for closing the switch, a magnet for opening the switch, contacts arranged in the path of the coin or token in such manner that first one magnet-circuit is closed and then another; and means for preventing the closing of the second circuit until after a certain interval.
5. In a coin or token controlled electrical apparatus, the combination of a circuit, a switch therein, a magnet for closing the switch, a second magnet for opening the switch, a winding for each of the magnets, through which less current is permitted to flow than in the said circuit, contacts for closing the circuits of the magnets in such a manner that the switch is first closed and then opened, all of said contacts being acted upon by the deposited coin or token, and means for retarding the passing of the coin so that there will be an appreciable time interval between the closing and opening of the switch.
6. In a prepayment mechanism for electric meters, the combination with a meter and the main circuit for its coil or coils, of a normally-open circuit-closer included in the meter-circuit, magnetically-controlled means for respectively opening and closing said circuit-closer, a coin - controlled device for setting into action the means for closing the circuit-closer, and a separate device also controlled by the coin for setting into action the means for opening said circuit-closer, substantially as set forth.
7. In a prepayment mechanism for electric meters, the combination with the register mechanism of the meter and the main circuit for the meter-coil, of a normally-open circuit-closer included in the meter-circuit, separate electromagnetic means for respectively controlling the opening and closing of said circuit-closer, a coin-controlled device for setting into action the means for closing the circuit - closer, and an automatic register - controlled device for moving the deposited coin to a point where it will set into action the means for releasing or opening said circuit-closer, substantially as specified.
8. In a prepayment mechanism for electric meters, the combination with the register mechanism of the meter, and the main circuit for the meter-coil, of a circuit-closer included in the meter-circuit and having a movable member, separate electromagnetic means for controlling the moving of said movable member of the circuit-closer to operative and inoperative positions, a coin-controlled device for setting into action the means for adjusting said movable member to an operative position and an automatic register-controlled

device for advancing the deposited coin to a point where it will set into action the means for releasing or moving said movable member to an inoperative position.

9. In a prepayment mechanism for electric meters, the combination with the register mechanism of the meter and the main circuit for the meter-coil, of a circuit-closer included in the meter-circuit and having a movable member, a main-circuit-closing armature carrying the movable member of the circuit-closer, an electromagnet for moving said armature in one direction, electrically - controlled means for regulating the moving of said armature in an opposite direction, a primary circuit-closer included in a circuit with said electromagnet and the main - line connections for the meter, a coin-controlled device for operating the primary circuit-closer, and a coin or token controlled device for automatically setting into action the means for moving said armature away from its magnet.

10. In a prepayment mechanism for electric meters, the combination with the register mechanism of the meter, and the main circuit for the meter-coil, of a circuit-closer included in said meter-circuit, and having a movable member, a main-circuit-closing armature carrying the movable member of said circuit-closer, an electromagnet for moving said armature in one direction, a separate electromagnet for regulating the moving of the armature in the opposite direction, separate local circuits for each of said magnets, a coin-controlled device for closing one of said local circuits, and a separate device also coin-controlled for closing the other of said local circuits.

11. In a prepayment mechanism for electric meters, the combination with the register mechanism of the meter, and the main circuit for the meter-coil, of a circuit-closer included in the meter - circuit and, having a movable member, a main-circuit-closing armature carrying the movable member of the circuit-closer, an electromagnet for moving said armature in one direction, a separate electromagnet for permitting the armature to move in the opposite direction, separate local circuits for each of said magnets, a coin-controlled device for one of the local circuits, and a coin-controlled device regulated by the register for automatically closing the other of said local circuits.

12. In a prepayment mechanism for electric meters, the combination with the main circuit, of a circuit-closer included in said circuit and having a movable member, a main-circuit-closing armature carrying the movable member of said circuit-closer, an electromagnet for moving said armature in one direction, a separate electromagnet for permitting said armature to move in the opposite direction, coin-controlled means for causing one of said magnets to be energized, and separate means acted upon by the coin for

- causing the other of said magnets to be separately and independently energized.
13. In a prepayment mechanism for electric meters, the combination with the main circuit, of a circuit-closer included in said circuit and having a movable member, a main-circuit-closing armature carrying the movable member of said circuit-closer, an electromagnet for moving said armature in one direction, a locking device pivotally supported at one end and having locking engagement at its other end with said main armature, an electromagnet arranged adjacent to the locking device for controlling the movement thereof in one direction, a spring, separate local circuits for each of said magnets, a coin-controlled device for closing one of said local circuits, and a separate device acted upon by the same coin which controlled the closing of the first circuit for closing the other of said local circuits.
14. In a prepayment mechanism for electric meters, the combination with the register mechanism of the meter and the main circuit for the meter-coil, of a circuit-closer included in the meter-coil circuit and having a movable member, a main-circuit-closing armature carrying the movable member of the circuit-closer, a setting-magnet for moving the main armature in one direction, a locking device pivotally supported at one end and having a loose locking engagement at its other end with the main armature, a release-magnet for controlling the movement of the locking device in one direction, a spring for moving the circuit-closing armature against the action of the magnet, a circuit-closer actuated by the deposited coin for setting the magnet into operative condition, and a coin-actuated circuit-closer, regulated in its action by the register mechanism, and included in a circuit with the release-magnet.
15. In a metering device, the combination of a coil or coils included in a circuit, a switch which is normally open included in the meter-circuit, coin and magnetically controlled means for regulating the opening of the switch, and coin and magnetically controlled means for regulating the closing of the switch.
16. In a metering device, the combination of a coil or coils included in a circuit, a switch which is normally open included in the meter-circuit, magnetically-controlled means for regulating the opening of the switch, magnetically-controlled means for regulating the closing of the switch, and coin-controlled

means for rendering both of the magnetic means operative.

17. In a prepayment mechanism, the combination of a main circuit, a circuit-breaker having a movable member, an armature carrying the said member, two magnets which act to control the armature, and separate coin-controlled devices for controlling the action of the magnets.

18. In a coin or other token controlled apparatus, the combination of two normally-open circuits, contacts for closing the circuits a register mechanism and means for directing the passage of the coin or other token through the register in such manner that it causes the closing of both circuits.

19. In a coin or other token controlled apparatus, the combination of two normally-open circuits, contacts for closing the circuits, a register, and a chute for directing the movement of the coin or token in such manner that the coin or token closes one circuit before entering the register, and the other after leaving the register.

20. In a coin or other token controlled apparatus, the combination of two normally-open circuits, a magnet included in each of the normally-open circuits and arranged to perform useful work, a chute for directing the movements of the coin or token, and contacts located near the chute and arranged to be pressed into engagement with each other for closing the circuit of magnets as the coin passes along; the arrangement being such that the circuit of first one magnet is closed, and then the other, the same coin or token acting in both cases.

21. In a coin or other token controlled apparatus which is capable of receiving more than a single coin or token, the combination of a magnet for closing a main circuit, a magnet for opening the circuit, means located in the path of the coin or token for closing both of the magnet-circuits, and means for permitting the second coin or token to advance to a point where it completes the closing of the circuit of the first magnet prior to the time that the first coin completes the circuit of the second magnet, so that there is no interruption of the main circuit.

In witness whereof I have hereunto set my hand this 5th day of April, 1899.

FRANK P. COX.

Witnesses:

DUGALD MCKILLOP,
HENRY O. WESTENDARP.
